UNITED STATES PATENT OFFICE.

FREDERICK SHICKLE, OF ST. LOUIS, MISSOURI.

PIPE-MOLDING APPARATUS.

SPECIFICATION forming part of Letters Patent No. 349,461, dated September 21, 1886.

Application filed August 17, 1885. Serial No. 174,653. (No model.) Patented in England November 24, 1885, No. 14,401; in Belgium December 15, 1885, No. 71,014, and in France February 24, 1886, No. 172,554.

To all whom it may concern:

Be it known that I, FREDERICK SHICKLE, of St. Louis, Missouri, have made a new and useful Improvement in Pipe-Molding Apparatus, of which the following is a full, clear, and exact description.

The improvement relates to the means used in forming the socket end of the mold.

It also relates to the means for centering the rammers at the upper end of the flasks, and for guiding them in their upward movement through the flasks.

It also has reference to the means for forming the bead-ring, and for closing the upper end of the flask during the ramming.

The annexed drawings, making part of this specification, illustrate the various features of the improvements.

Figure 1 is an elevation, half in section on the line 1 1 of Fig. 2, showing the flask upon the ramming-stand as when the flask is to be rammed. Fig. 2 is a plan, half in section on the line 2 2 of Fig. 1, of the flask. Fig. 3 is a plan, half in section, the section being taken on the line 3 3 of Fig. 1, of the ramming-stand.

Fig. 4 is a view in perspective of the removable plate used upon the upper end of the flask in ramming it. As exhibited, the plate contains the prints for forming the recess for the reception of the bead-ring, and the plate is shown resting in position upon the flask-body.

The same letters of reference denote the same parts.

The improvement in question is adapted more especially to flasks in which the pipes are cast the socket end downward, and to cluster flasks, in distinction from single flasks. Various features of the improvement, however, are adaptable to pipes otherwise cast and in single flasks, as will more fully appear upon further consideration.

A, Figs. 1, 3, represents the ramming-stand. Its frame-work consists, essentially, of the base a , the upright a' , and the top a'' .

The cluster flask shown is a four-part one, and the ramming-stand is correspondingly constructed, to which end it is provided with four similar ramming appliances, as follows: Four spindles, a^3 a^3 a^3 a^3 , are each stepped at

a^4 a^4 in the base a , and in such manner as to be held upright therein, and to be capable of being rotated therein. Each spindle is provided with a sleeve, a^5 , which can be slipped vertically upon the spindle. The sleeve, by means of the arms a^6 , upholds a ring, a^7 , that is adapted to be moved upward and downward a short distance in an opening, a^8 , in the top a'' . The ring a^7 , in turn, contains and upholds another ring, a^9 , whose shape externally is suited for forming the socket on the pipe to be cast. Arms a^{10} a^{10} at one end are journaled upon bearings a^{11} upon the spindle, and at the other end are jointed, respectively, to the arms a^{12} a^{12} , which extend upward, and are adapted to connect with and uphold the sleeve a^5 . The two pairs a^{10} a^{12} and a^{10} a^{12} form two toggles, which can be straightened and bent, and when straightened operate to lift the sleeve, and when bent operate to lower the sleeve upon the spindle.

One mode of connecting the toggles with the sleeve is to let the upper ends of the arms a^{12} bear upward against a shoulder, a^{13} , upon the spindle, and to connect the arms a^{12} a^{12} by means of a bolt, a^{14} , which passes transversely through the arms a^{12} , the sleeve, and a slot, a^{15} , in the spindle. The slot is elongated vertically, to provide for the needed vertical movement of the sleeve.

By means of a lever, a^{16} , which is attached to the sleeve, and also connected with the arms a^{10} a^{10} , the spindle can be rotated in its step a^4 , and the toggles straightened and bent, the operation of this part of the construction being as follows: B represents the flask to be rammed. It is placed upon the ramming-stand so that its several compartments b b b b shall respectively come properly into coincidence with the openings a^8 a^8 in the ramming-stand top a'' . The rammer C is dropped through the compartment b , and through the ring a^7 , and its lower end rests upon the spindle a^3 , which at that point is preferably supplied with a vertically-adjustable screw, a^{17} , for the purpose of vertically adjusting the rammer. The sand D is placed in the compartment around the rammer and the ring a^7 . Then by throwing the free end of the lever a^{16} upward the rings a^7 a^9 are

lifted upon the rammer and within the compartment *b*. The sand is thereby rammed in an upward direction in the lower end of the compartment, and thus a portion of the mold which forms externally the socket of the pipe is constructed. After this part of the sand has been thus rammed the rings *a' a'* are withdrawn downward into their original position; but as the sand is liable to break away if the rings are at once drawn downward the rings are first rotated in a horizontal direction within the compartment and then withdrawn. This is done by means of the lever *a¹⁶*, which is vibrated horizontally, causing the sleeve and rings *a' a'* to be rotated reciprocatingly, and so as to part the sand from the rings, after which the lever *a¹⁶* is thrown downward and the rings withdrawn. This is not done, however, until after the rammers are withdrawn. The sand in each of the compartments *b b b* is similarly rammed, after which the sand throughout the main portion of the compartments is ready to be rammed. This is effected by means of the rammers *C C C C*, respectively, Figs. 1, 2. The rammers are similar to those described by me in the Letters Patent granted me November 27, 1883, numbered 289,035, and the ramming is effected by drawing the rammer upward from off the screw *a¹⁷* and through the ring *a⁹*, and thence upward through the flask, substantially as in the Letters Patent referred to.

In the manipulation of the rammers several points must be attended to. In placing them in their respective compartments *b*, they must be properly centered at the top of the flask-compartments. To this end the yoke *C'*, which unites the rammers of the flask, is provided with a pin, *C²*, which, when the rammers are dropped into the compartments *b*, passes downward into a perforation, *b'*, that is at the center of the flask at the top, and that extends downward through the removable top *E* of the flask, and also through the part of the flask beneath the removable top. The engagement of the pin, as described, centers the clusters of rammers, and the various rammers are respectively properly centered in the compartments *b b b b* by means of the frame *F* and the prints *G*. The frame is properly shaped, in the present instance being arranged to brace the rammers, as shown in Figs. 1, 2, respectively, centrally in their respective compartments, the frame for that purpose consisting of the four bars *f f*, attached to an interior frame, *f'*, Fig. 2, and at their ends *f²* abutting against the rammers, and also being turned downward, as shown at *f³*, Fig. 1, to fit between the prints *G* and the rammer. The prints *G* are annular in form, and in diameter are equal to that of the largest part of the rammer, or of that of the finished mold at the upper end. They are beveled at *g*, and are furnished with a flange, *g'*, Fig. 1, which comes against the under side of the removable plate *E*. This plate or top has openings *e*, to receive the prints from beneath, as represented in Figs. 1, 2, 8. The openings are respect-

ively coincident with the compartments *b*. The top *E* is adapted to be secured during the ramming and, by means of suitable clamps, to the flask-body *b'*. The top *E* holds the prints down against the upward pressure exerted by the rammer. The frame *F*, by means of the buttons *f³*, Figs. 2, 8, is adapted to be held down upon the top *E*. By this means, when the sand within the compartments is being crowded upward by the action of the rammer, the top *E* both prevents the sand from being uplifted from its place and holds the prints and centering-frame *F* down in position. The flask being rammed is made ready for the casting operation, to which end the socket-forming rings are drawn downward by means of the ramming-stand mechanism, the bead-rings are placed in position, and the mold black-washed and set upon the bottom and clamped thereto, and then swung into the oven and dried, after which it is hung upon the pit-wall, the cores inserted, and the appliances at the upper end of the flask for completing that part of the mold, and for directing the flow of the molten metal, are placed in position.

The flask is set upon and removed from the ramming-stand in the ordinary manner and with the customary means.

The flask shown is made in four parts. Each pair of said parts is divided vertically and diametrically and hinged together—one pair at *b³⁰*, the other pair at *b⁴*. The inner and contiguous parts of each pair may be riveted or otherwise secured together.

The flask is hung upon the pit-wall by means of the hanger *O* and brace *P*.

I claim—

1. The ramming-stand *A*, having the spindle *a³* and the sleeve *a⁵*, said sleeve being adjustable vertically and capable of being turned around with said spindle, for the purposes described.

2. The ramming-stand *A*, having the spindle *a³* and the sleeve *a⁵*, said sleeve being capable of being turned around with said spindle, for the purpose described.

3. The combination of the stand *A*, the flask *b*, the ring *a⁹*, the spindle *a³*, and the vertically-adjustable sleeve *a⁵*, having the ring *a⁹*, as described.

4. The combination of the stand *A*, the flask *b*, the ring *a⁹*, the spindle *a³*, and the vertically-adjustable and rotatable sleeve *a⁵*, as described.

5. The combination of the stand *A*, the flask *b*, the ring *a⁹*, the spindle *a³*, and the sleeve *a⁵*, said sleeve being capable of being turned around.

6. The combination of the stand *A*, the spindle *a³*, the sleeve *a⁵*, having the ring *a⁷*, the ring *a⁹*, and the flask *b*, said sleeve and ring being movable vertically, for the purpose described.

7. The combination of the stand *A*, the spindle *a³*, the sleeve *a⁵*, the ring *a⁷*, the ring *a⁹*, and the flask *b*, as described.

8. The combination of the stand *A*, the spin-

dle a^3 , the sleeve a^5 , the arms $a^{10} a^{12}$, and the lever a^{16} , as described.

9. The combination of the stand A, the spindle a^3 , the slotted sleeve a^5 , the arms $a^{10} a^{12}$, the bolt a^{14} , and the lever a^{16} , as described.

10. The combination of the stand A, the spindle a^3 , the sleeve a^5 , the arms $a^{10} a^{12}$, the bolt a^{14} , the rings $a^7 a^9$, the lever a^{16} , and the flask b, said sleeve having a shoulder, against which the arms a^{12} at their upper ends abut, and said spindle being slotted, as described.

11. The combination of the stand A, the flask b, the ring a^9 , the spindle a^3 , the arms $a^{10} a^{12}$, and the sleeve a^5 , said sleeve having the ring a^7 , and also a shoulder, against which the arms a^{12} at their upper ends abut, as described.

12. The combination of the stand A, the flask b, and the rings $a^7 a^9$, being upheld by a part that is vertically adjustable in said stand and that can be turned around horizontally.

13. The combination of the cluster flask B, the rammers C C, the yoke C', and the pin

C^2 , adapted to enter the perforation b' , as and for the purpose described.

14. The combination of the cluster flask B, the rammers C C, the frame F, the top E, and the prints G G, as described.

15. The combination of the cluster flask B, the rammers C C, the yoke C', the pin C^2 , the perforated part b' , the top E, the frame F, and the prints G G, as described.

16. The combination of the cluster flask B, the removable top E, and the prints G G, fitting within the openings of said top, as described.

17. The combination of the cluster flask B, the top E, the rammers C C, and the frame F, substantially as described, and for the purpose set forth.

Witness my hand.

FREDERICK SHICKLE.
